UNITED STATES PATENT OFFICE.

WILLIAM RADCLIFF, OF PHILADELPHIA, PENNSYLVANIA.

BOILER.

1,283,186.

Specification of Letters Patent. Patented Dec. 17, 1918.

Application filed September 6, 1917. Serial No. 190,063.

To all whom it may concern:

Be it known that I, WILLIAM RADCLIFF, a citizen of the United States of America, residing in the city and county of Philadelphia, in the State of Pennsylvania, have invented certain new and useful Improvements in Boilers, of which the following is a true and exact description, reference being had to the accompanying drawings, which

form a part thereof.

My present invention relates to boilers, and the object of the invention is to provide an improved boiler setting characterized on the one hand by its greater resistance to deterioration under the conditions of use, and on the other hand to its increased efficiency and capacity.

In carrying out my invention I place metallic water receptacles at the opposite sides of the combustion space of the boiler furnace. These receptacles are separate from the tubular boiler proper, but are connected to, and form a part of the water circulating system of the boiler, and are embedded in and form parts of the side walls of the boiler furnace. These receptacles perform the double purpose of increasing the metallic wall surface exposed on the one side to the hot gases of combustion, and in contact on the other side with the water to be vaporized, and of preventing the deterioration and settling of the boiler walls at the sides of the combustion chamber occurring when the supporting walls are formed entirely of masonry in the usual manner, are employed.

A further object of the invention is to combine with the water receptacles at the side of the combustion chamber an efficient water cooled arch extending over the combustion chamber proper and serving thereby to protect the boiler proper from local overheating and to improve the character of the combustion.

The various features of novelty which characterize my invention are pointed out with particularity in the claim annexed hereto and forming a part of this specification. For a better understanding of the invention, however, and the advantages possessed by it, reference should be had to the accompanying drawings and descriptive matter in which I have illustrated and described a preferred embodiment of my invention.

55 Of the drawings:

Figure 1 is a front end elevation of a

boiler with a portion of the front wall of the boiler broken away and removed to render the interior of the boiler visible.

Fig. 2 is a longitudinal section on the broken line 2—2 of Fig. 1.

In the drawings I have illustrated the use of my invention in the boiler of the return tubular type though it is to be understood that my invention, in its broader aspects, is well adapted for use with water tube and other types of boilers differing from that illustrated. In the construction illustrated A represents the boiler housing and B the front end wall thereof. B' and B² are fire and ash doors respectively. At the sides of the boiler are the usual masonry side walls C. D represents a return tubular boiler proper of conventional form provided with brackets D', which rest upon the upper edges of the wall C. A' represents the outlet for smoke, A² the combustion chamber proper, A³ the back arch preventing the products of combustion passing along the under side of the boiler to the rear end of the latter, from passing directly into the smoke outlet A' without passing through the fire tubes D² of the boiler. A⁴ represents the usual bridge wall at the rear end of the combustion chamber proper. In so far as above described, and except for peculiarities of the walls C, yet to be explained, the boiler shown possesses nothing now novel with me, but on the contrary is of a well known type long in common use.

The boiler side walls C instead of being formed wholly of masonry, as is commonly the case, are each formed in part by a flattened drum or water leg E. Each flattened water drum is advantageously of a width, measured transversely to its flat sides, approximately equal to that of the remainder of the wall C, and is formed with rounded top and bottom edges and has its flat sides connected by stay bolts E'. Each flattened drum E extends horizontally from the front end of the boiler to a slight distance beyond the bridge wall A⁴, and extends vertically from a level below, to a level above the combustion chamber proper of the furnace. The water drums E are connected by tubes E², E³, E⁴, E⁵ and E⁶ to the interior of the boiler D, some of these tubes opening to the boiler below the water level therein and others above the water level. The two drums E of each furnace are also connected by a series of curved tubes F which are

bowed upwardly over the combustion chamber A² and open into the drums E adjacent the upper edges of the latter. On the tubes F are arranged suitably shaped brick G to 5 form an arched roof over the combustion chamber. This arched roof is separated from the boiler D proper by a space A⁵; and an opening G', formed in the roof by omitting some of the bricks G adjacent the front 10 end of the combustion chamber, permits a portion of the hot products of combustion to pass upwardly out of the combustion chamber into the space A⁵ through which they flow lengthwise of the boiler and eventually merge with the bulk of the products 15 leaving the combustion chamber over the bridge wall A⁴ at the rear of the arch. The products of combustion passing through the space A⁵ heat the front end of the boiler. 20 The masonry wall A⁶ supported on the front end of the arch brick G prevents products of combustion from passing out of the front end of the space A⁵ up past the front end of the boiler. Mud cleanout doors E⁷ are 25 provided in the front ends of the drum E. D⁸ represents the steam pipe of the boiler and E⁹ the water feed line to the boiler which opens to one of the drums E.

With the construction described the tubes 30 E², E³, E⁴, E⁵ and E⁶ when suitably proportioned and arranged insure an energetic circulation through the water drums E effective to prevent any appreciable accumulation of steam in, and destructive over- 35 heating of the drums E and the tubes connected thereto. At the same time the surface of the drums and the tubes connected thereto exposed to the heat of the combustion chamber, materially augments the heating 40 surface of the boiler and increases its capacity. The drums proportioned and arranged in the manner illustrated are easily made of ample strength to support the masonry portions of the walls C above them 45 and the load carried thereby, and in practice the drums E and the tubes connected thereto will stand up indefinitely under the conditions to which they are subjected. The use of the drums E, therefore, avoids the crumpling and settling of the portions of boiler 50

supporting walls at the sides of the combustion furnace occurring when these walls are made wholly of brick work. This is of especial importance in boiler settings, which, as in the return tubular boiler shown, the 55 weight of the boiler proper is carried in whole or in part by the side walls of the boiler housing.

The water cooled arch, formed by the tubes F and brick G, protects the adjacent 60 portion of the boiler proper from being directly subjected to the heat of the hottest portion of the combustion chamber and thereby prolongs the life of the boiler proper, and in addition the subdivision and 65 reuniting of the products of combustion in the manner described improves combustion and in particular facilitates the combustion of imperfectly burnt gases leaving the combustion chamber over the bridge wall A. 70

While in accordance with the provisions of the statutes I have illustrated and described the best form of my invention now known to me, it will be apparent to those skilled in the art that changes may be made 75 in the form of the apparatus disclosed without departing from the spirit of the invention claimed herein, and that certain features of the invention claimed may sometimes be used to advantage without a corresponding 80 use of other claimed features.

Having now described my invention, what I claim as new and desire to secure by Letters Patent, is:

In a boiler setting, the combination with 85 the boiler proper, of side walls made up of upper and lower masonry portions and an intervening portion in each side wall formed of flattened water drums upon which the upper masonry portions are supported, and 90 which water drums form the side walls of the combustion chamber, circulating connections between the water drums and the boiler, arched tubes extending over the combustion chamber and connecting the water 95 drums, and masonry supported on said tubes and forming a top for the combustion chamber.

WILLIAM RADCLIFF.
